UNITED STATES PATENT OFFICE.

EVA J. DAVIDSON, OF CHICAGO, ILLINOIS.

INFANT'S GARMENT.

Specification of Letters Patent. Patented Aug. 22, 1916.

1,195,565.

Application filed September 7, 1915. Serial No. 49,376.

To all whom it may concern:

Be it known that I, EVA J. DAVIDSON, a citizen of the United States, and a resident of Chicago, in the county of Cook and State of Illinois, have invented certain new and useful Improvements in Infants' Garments; and I do hereby declare that the following is a full, clear, and exact description thereof, reference being had to the accompanying drawings, and to the letters of reference marked thereon, which form a part of this specification.

This invention relates to infants' and like garments, and also the method of making the same.

Among the objects of my invention is to improve the construction of garments of the kind referred to, in the several particulars as will hereinafter more fully appear, and to provide in particular a novel method, whereby the body portions of such garments may be made from a single piece of material and when made have but a single seam.

25 The invention also relates to the method of making patterns from which such garments may be made.

The invention consists further in the materials hereinafter described and more particularly pointed out in the appended claims.

In the accompanying drawings—Figure 1 is a plan view of a square piece of material from which a garment embodying the features of my invention may be made; Fig. 35 2 is a plan view showing said piece of material folded diagonally upon itself; Fig. 3 is a rear elevational view of an infant's dress or outer garment made in accordance with my invention; Fig. 4 is a transverse sectional view taken on line 4-4 of Fig. 3; and Fig. 5 is a perspective view of an infant's underskirt or like garment made in accordance with my invention.

In Fig. 3 of the accompanying drawings I have shown an infant's dress or outer garment 10 constructed in accordance with my invention, and, as illustrated, said dress 10 comprises a tubular body portion 11 made from a single piece of material, the meeting edges of which are sewed together by a line of stitching 11^a at the back of said garment, thereby forming the only seam 12 in the body of the garment. Said garment 10 is provided with two sleeves 13, 14 and

55 with a placket opening 15 at the back thereof. Said placket 15 is in the upper part of the garment and is formed by the upper portions of the meeting edges of the material being left disconnected. Said placket 15 may be provided with any suitable type of fastening devices for closing the same, such as snap fasteners 16, 17 as shown in said Fig. 3.

The dress 10, shown in Fig. 3, may be made from a pattern cut in accordance with my novel method, or said garment may be made from the material without the use of a pattern. For the sake of presenting a clear understanding of my invention, I will first describe in detail the manner of making 70 said dress 10 without the use of a pattern.

To make the garment 10 without a pattern, I cut from a bolt of cloth or the like a square piece of material 18, such as shown in Fig. 1. As illustrated, said square piece 75 of material 18 has two selvage edges 19, 20 oppositely disposed, and two raw edges 21, 22 also oppositely disposed. Said raw edges 21, 22 constitute the edges along which the piece of material 18 is cut from the cloth, 80 and the selvage edges are the side edges of the cloth as manufactured. It is of course to be understood that said piece of material 18 may be cut from a piece of cloth of such width that all of its edges will be raw edges. 85 For the purpose of illustration, however, I will consider that said piece of material 18 has two selvage and two raw edges as described. Said square piece of material 18 is first laid flatwise with its right side facing 90 downward in order that the right side of the garment when completed will be outermost. In case the material is finished the same on both sides, then either side thereof may be placed downward. The next step is to fold 95 the square piece of material 18 diagonally upon itself along a diagonal fold line substantially connecting two diagonally disposed corners, so as to bring a selvage edge along a raw edge. As illustrated in Fig. 1, 100 the diagonal fold line is indicated by the dotted line 25, and when the material is folded along such line, the raw edge 21 is brought over and along the selvage edge 19 and with the corner 23 over the diagonally opposite corner 24. The piece of material so folded is shown in Fig. 2, and it will be noted that the portion or flap 26 thereof between the

line of fold 25 and the corner 23 overlaps that portion or flap 27 between said fold line 25 and the opposite corner 24. As illustrated, each flap 26, 27 is triangular in shape, and the former is above the latter. In order that the selvage edge 19 may project slightly beyond the raw edge 21, the material is folded so that the fold line 25 does not directly connect the diagonally disposed corners 28, 29, but is offset laterally a slight distance toward the said corner 23. By thus folding the material, the selvage edge 19 projects beyond the raw edge 21.

After the piece of material 18 has been folded upon itself, as shown in Fig. 2, I measure along the raw edge 21 from the selvage edge 20 a distance equal to the length of the garment to be made, including in such length the width of its hem at the bottom thereof. By the length of the garment, I mean the length of the body of the same along its rear face from the edge of the neck opening to the bottom of the hem; in other words, the length such as would be along the seam 12, shown in Fig. 3. At the end of this distance I place a mark, such as 29^a, on the margin of said raw edge 21. This distance in the garment shown in Fig. 3 would be from the bottom of the garment, including the width of the hem, to the edge of the neck opening thereof. Taking the entire length of the raw edge 21 as a radius and the corner 28 as a center, I describe an arc, such as indicated by the dotted line 30 in Fig. 2, on the uppermost flap 26. Such arc 30 extends from the substantially coinciding corners 23, 24 to the line of fold 25. While the material is folded, I next mark off from the mark 29^a a development of one-half of the neck opening of the garment, including a development of one arm-hole. Such developments are indicated by the dotted lines 31 and 32, respectively. As the neck opening for the dress 10 is lower in the front than in the back, it follows that the distance from the base line 30 to the neck line 31 along the line of fold 25 is less than the distance between such lines along the raw edge 21. In that portion 33 of the flap 26 between the base line 30 and the substantially coinciding edges 20, 22 I mark out a line development of one of the sleeves of the garment, and such development is indicated in Fig. 1 by the connected dotted lines 34, 35, 36, 37, and 38. The last two lines are connected by the raw edge 21, as shown.

After marking on the uppermost flap 26 of the folded material the base line 30, the neck opening, and arm-scye lines 31 and 33, respectively, I cut the folded material along such lines and thus form the body portion 11 of the garment. I then cut out of the folded material the sleeves 13, 14 along the lines 34 to 38, both inclusive. As the mate-

rial is folded, it follows that both sleeves are cut out at the same time. After cutting out the body of the garment, and while the flaps 26, 27 are still overlapped, I fold the selvage edge 19 over and upon the raw edge 21, so that the former covers and protects the latter. Such folded edges are then stitched or sewed together from the coinciding corners 23, 24 toward the corner 28 to about a point marked "x", which, as shown in Fig. 2, is a distance below the neck opening edge 31. Between the point "x" and the neck opening edge 31, the margins of the edges 19 and 21 remain disconnected and constitute the placket opening 15 at the back of the dress 10. To the opposite facing margins of the placket are sewed the snap fasteners 16, 17 above referred to. After the sleeves are cut out, the same are folded centrally upon themselves, so as to bring the edges 34 and 38 thereof together. Each sleeve is sewed along such edges and set in the arm-hole of the body of the garment. Each sleeve, as shown, is sewed along its edges 35 and 37 to the edge of the arm-hole, and the edge 36 forms the edge of the neck opening across the arm-scye. The bottom of the body of the garment formed by the base line 30 is turned inward and sewed to form the hem 39, such as shown in said Fig. 3.

It will be noted that the garment 10 so made is provided in the body 11 thereof with but one seam, and that at the back of the same. It follows, therefore, that the body of the garment may be easily made and, further, with a saving in material used, as the sleeves are cut from the same piece of material from which the body of the garment is made. Moreover, the selvage edge 19 being turned over the raw edge 21 at the seam, the selvage edge protects the raw edge, and it is not necessary to overcast such raw edge.

I have described in detail above, the manner of making the dress 10 wherein the seam 12 is in the back. In making an infant's night-gown, however, it is desirable that the seam be in the front. In such case, the square piece of material from which the night-gown is to be made is folded in the same manner as hereinbefore described as shown in Fig. 2, except that the distance between the neck line and the base line 30 along the fold line 25 will be greater than the distance between said neck line and said base line along the overlapping edges 19, 21. This is necessary, because in a night-gown the neck opening is usually lower in the front than in the back.

In Fig. 5, I have shown an infant's petticoat 40 made from a single piece of material and in accordance with my novel method. As illustrated, the seam 41 is the only seam

in the body of the garment, and such seam may be either in the front or in the back thereof. In either case, said seam extends from the base of the garment to the neck opening thereof and is devoid of a placket. The garment 40 shown in Fig. 5 is sleeveless, but is provided with shoulder straps 42, 43 detachably connected together by loops 44, 44 on one part and buttons 45, 45 on the adjacent part.

Fig. 4 shows a cross-section of the seam 12 and illustrates the manner in which the folded edges 19 and 20 are stitched together.

The foregoing describes the manner of 15 making the garment 10 without the use of a pattern, but, in case a pattern is to be used, the pattern is made in accordance with my novel method as follows: I take a square piece of paper or the like and fold it diagonally upon itself, as shown in Fig. 2. Then 20 I lay out one-half of the development of the neck opening, including the arm-scye, as described, and then describe the arc for the bottom edge of the pattern. I also lay out, 25 on the folded material and below the base line of the pattern, the development for one sleeve. After laying out the development lines on the folded paper, I cut out the patterns along such lines for the body portion 30 and sleeves of the garment. In making a garment from such patterns, a piece of material such as 18 is spread out flatwise, as shown in Fig. 1, and the spread out patterns placed thereon. The material is cut around 35 the edges of said patterns, and after being cut out, the garment is made as described. In said Fig. 1, I have shown, in dotted lines, the patterns so made and laid out on a square piece of material.

40 Instead of making and laying the full pattern out flatwise on the spread out piece of material, and cutting around the edges of the pattern, as above described, I may make a garment by using only half of a full pattern, laying the same on the folded material, and then cutting the folded material around the edges of the pattern.

Whether marking the development or outlines of the neck opening and the bottom 50 edge of the garment to be made on the folded material, or first cutting out the body of the garment and sleeves thereof from the flat piece of cloth from a pattern, it will be noted that the body of the garment so made 55 has but one seam and may be readily made with the expenditure of a small amount of labor and with a minimum amount of material.

Although I have shown and described in 60 detail one manner in which my invention may be carried out, yet it is to be understood that I may change and variously modify the details of construction and arrangement of parts shown without departing from the spirit and scope of my invention.

tion, and I do not wish to be limited to the details shown and described, except as pointed out in the annexed claims.

I claim:

1. The method of making a garment, consisting in, first, taking a square piece of material, second, folding said square piece of material centrally and diagonally upon itself, so as to bring the edges of said material on one side of said diagonal fold line 75 over and alongside of the corresponding edges of said material on the opposite side of said diagonal fold line and thereby making the folded material triangular in shape and giving the body of the garment cut from 80 said folded material a flared form, third, cutting from said folded material the body of the garment along lines indicating the edge of the neck opening and bottom edge of said garment and extending between two 85 overlapping edges of the material and said diagonal fold line, and, fourth, sewing together those overlapping edges of the material that extend between the bottom edge of the garment and its neck opening. 90

2. The method of making a garment, consisting in, first, taking a square piece of material having two oppositely disposed selvage and raw edges, second, folding said square piece of material centrally and diagonally upon itself, so as to bring a raw edge of said material adjacent to and alongside of a selvage edge thereof, third, cutting from said folded material the body of the garment along lines indicating its neck opening and bottom edge and extending between said diagonal fold line and said overlapping raw and selvage edges, fourth, turning said selvage edge extending between the neck opening and the bottom edge of the garment 105 over and upon said adjacent raw edge, and, fifth, sewing together said overlapping selvage and raw edges. 110

3. The method of making a pattern for a garment, consisting in, first, taking a square 115 piece of material, second, folding said square piece of material centrally and diagonally upon itself, so as to bring the edges of said material on one side of said diagonal fold line over and alongside of the corresponding edges of said material on the opposite side of said diagonal fold line and thereby making the folded material triangular in shape and giving the body of the garment to be made by the use of said pattern a flared form, third, marking on one of the overlapping flaps of the folded material at 120 a distance from one of the corners to which said diagonal fold line extends a line extending between two overlapping edges of said 125 material and said diagonal fold line and indicating one-half of the development of the neck opening of the garment, fourth, taking said corner as a center and the overlapping edges 130

extending thereto as a radius and marking on one of the flaps of the folded material an arc-shaped line extending between said overlapping edges and said diagonal fold line and indicating one-half of the development of the bottom edge of the garment to be made by the use of the pattern, and, fifth, cutting the pattern from said folded material along the lines marked thereon and indicating, respectively, the neck opening and

bottom edge of the garment to be made by the use of said pattern.

In testimony that I claim the foregoing as my invention, I affix my signature in the presence of two witnesses, this 4th day of 15 September, A. D. 1915.

EVA J. DAVIDSON.
